US00D939693S

(12) **United States Design Patent** (10) **Patent No.:** **US D939,693 S**
Kern et al. (45) **Date of Patent:** **** Dec. 28, 2021**

(54) **DRUG DELIVERY DEVICE**

(71) Applicant: **Sanofi-Aventis Deutschland GMBH**,
Frankfurt am Main (DE)

(72) Inventors: **Daniel Kern**, Frankfurt am Main (DE);
Udo Stauder, Frankfurt am Main (DE);
Marc Holtwick, Frankfurt am Main (DE);
Steffen Raab, Frankfurt am Main (DE)

(73) Assignee: **Sanofi-Aventis Deutschland GMBH**,
Frankfurt am Main (DE)

(**) Term: **15 Years**

(21) Appl. No.: **29/693,473**

(22) Filed: **Jun. 3, 2019**

Related U.S. Application Data

(62) Division of application No. 29/577,185, filed on Sep. 9, 2016, now Pat. No. Des. 850,613.

(57) **CLAIM**

The ornamental design for a drug delivery device, substantially as shown and described.

DESCRIPTION

The patent or application file contains at least one drawing executed in color. Copies of this patent or patent publication with color drawing(s) will be provided by the Office upon request and payment of the necessary fee.

FIG. 1 is a rear view of the drug delivery device;

FIG. 2 is a front view thereof;

FIG. 3 is a right side view thereof;

FIG. 4 is bottom view thereof;

FIG. 5 is a top view; and,

FIG. 6 is a perspective view thereof.

1 Claim, 6 Drawing Sheets
(6 of 6 Drawing Sheet(s) Filed in Color)
